UNITED STATES PATENT OFFICE.

CYRUS P. GIFFORD, OF ERIE, PENNSYLVANIA, ASSIGNOR TO JOHN J. GIBSON, OF ERIE, PENNSYLVANIA.

VENDING-MACHINE.

1,163,080.

Specification of Letters Patent.

Patented Dec. 7, 1915.

Application filed July 16, 1915. Serial No. 40,262.

To all whom it may concern:

Be it known that I, CYRUS P. GIFFORD, a citizen of the United States, residing at Erie, in the county of Erie and State of Pennsylvania, have invented certain new and useful Improvements in Vending-Machines; and I do hereby declare the following to be a full, clear and exact description of the invention, such as will enable others skilled in the art to which it appertains to make and use the same, reference being had to the accompanying drawings, and to the letters of reference marked thereon, forming part of this specification.

My invention relates to vending machines and has for its object the construction of a suitable receptacle for containing flat packets, and mechanism adapted to eject a single packet and also coin operated mechanism whereby said ejecting mechanism may be unlocked so as to be manually operated.

The features of my invention are herein-after fully explained and pointed out, and are illustrated in the accompanying drawings in which:

Figure 1, is a front view in elevation of my vending machine, with a portion of the same broken away. Fig. 2, is a top or plan view of the same, showing the ejecting mechanism open. Fig. 3, is a front view of the same, with the lower portion of the case broken away, showing the ejecting and locking mechanism in section. Fig. 4, is a transverse section of the same, on the line $x-x$ in Fig. 3, looking downward. Fig. 5, is a transverse section of the same on the line $y-y$ in Fig. 3, looking upward. Fig. 6, is a vertical section of the same on the line $z-z$ in Fig. 4, looking in the direction of the arrow.

In these drawings, A, indicates a box-like case, having a vertically sliding front, A', and α indicates a coin-slot in the front A'. Within the case A are vertical guide strips A² and A³ which are in spaced relation to the edge walls of the case, and operate to guide the packets placed in the case. The coin-slot, α , opens into the space between the guide strip, A³, and the edge wall of the case. Within the case, A, is a horizontal plate, B, (see Fig. 3) which is provided with a coin-slot, b, through which a coin may pass from the space between the guide strip A³ and the adjacent edge wall of the case. The plate, B, is somewhat above the bottom of the case, A, so as to leave sufficient space

under said plate for the reception of coins which pass through the slot, b. The plate, B, is also provided with a slot, B', (see Fig. 5) for the purpose hereinafter set forth. Upon the plate, B, I pivot, by means of a pivot b' ejector mechanism, consisting of a plate, B², having upturned side walls b². These side walls b² are of a width equal to the thickness of the packets which the machine is designed to vend. Secured to the rear end of the rear wall b² is a flat spring-strip C, which operates against the rear edge of the first packet above the one resting on the ejector plate, B², between its upturned walls, b², and presses it against the front wall of the case to prevent the column of packets from moving downward when the ejector is swung open as shown in Fig. 2. Pivoted to the back wall of the case, A, behind the ejector plate, B², is an arm, D, which projects through an opening, c, in the rear upturned edge b², of the plate, B², so that when the ejector plate, B², is opened the free end of the arm, D, will swing forward toward the free end of the plate, B², and force the packet resting on the plate, B², longitudinally forward on the plate, B², as shown by broken lines in Figs. 2 and 4, and when the plate, B², is closed said arm, D, will be returned to its normal position, as shown by full lines in Fig. 4, so that the next upward packet can move downward into place on the plate, B², in front of the arm, D. To cause the plate, B², to swing back into the case, A, after a packet has been removed therefrom, I provide a spring, E, (see Fig. 4), which is secured to the rear wall of the case, A, so that its free end will press against the edge of the plate, B², back of the pivot, b'. To limit the outward movement of the plate, B², I secure thereto a depending stud-pin, F, which extends through the slot, B', in the plate, B. For the purpose of preventing the operation of the ejector plate, B², until a coin has been deposited, I provide a balanced, horizontally tilting, plate, G, which is supported under the plate, B, by means of a pivot, G', which passes through ears on the plates, B and G, (as shown in Figs. 3 and 6); one end of the tilting plate, G, is provided with an upwardly projecting stud or bolt, G², which extends through holes in the plate, B, and ejector plate, B², which holes coincide when the ejector plate is closed.

Secured on the under side of the tilting plate G, is a flexible spring strip, H, one end of which is fastened to the plate, G, by means of rivets, h, as shown in Fig. 5, and the other end of which is slidably supported by a U-shaped loop, h', with the extremity of said spring strip, H, projecting nearly across the coin-slot, b, (as shown in Figs. 4 and 5). I also provide a short spring strip, H', (see Figs. 4 and 5) which is secured to the tilting plate, G, and which projects nearly across said coin-slot, b, and is in spaced relation to the outer end of the strip, H, and only sufficiently near thereto to catch and hold a coin of the desired dimension between the ends of said strips, H and H', while permitting coins of less diameter to pass therebetween.

In operation, when the receptacle has been filled with a quantity of packets, as shown in Fig. 6, a coin of the proper denomination may be inserted into the slot, a, which coin will drop down through the slot, b, and will engage the ends of the spring-strips, H and H', and the weight of said coin will cause the plate, G, to tilt, as shown by broken lines in Fig. 3, which will draw the upwardly projecting stud or bolt, G², downward out of the hole in the ejector plate, B². The ejector-plate, B², is then manually caused to swing outward as indicated in Figs. 2, 4 and 5, the stud, F, moving from one end of the slot, B', to the other, and in its traverse engaging the curved spring-strip, H, and moving it to the position thereof shown by broken lines in Fig. 5, which will withdraw the free end of said strip backward out of engagement with the deposited coin, and permit said coin to drop into the space underneath said tilting plate, and when the packet has been removed from the ejector plate, B², the spring, E, will close the ejector plate, B², and the tilting plate will resume its normal position, with the bolt, G², projecting into the hole in the ejector plate, B², thereby preventing another movement of said plate, until another coin has been inserted, after which the operation may be repeated.

Having thus fully shown and described my invention so as to enable others to construct and utilize the same, what I claim as new and desire to secure by Letters Patent is;

1. The combination in a vending machine, of a receptacle adapted to maintain a supply

of packets in upright column, a horizontally swinging ejector plate adapted to receive the lowermost packet, a vertically movable lock-bolt, a coin operated tilting-plate horizontally pivoted below said ejector plate adapted to control said bolt, means secured on said tilting plate projecting into the path of and adapted to obstruct the passage of a coin, and mechanism adapted to withdraw said coin obstructing means from the path of a coin when said ejector plate is operated, substantially as set forth.

2. The combination in a vending machine of a receptacle adapted to maintain a supply of packets in vertical column, a horizontal division plate having a coin slot therethrough, an ejector plate pivoted on said division plate, and adapted to receive the lowermost packet, a lock-bolt to normally lock said ejector-plate, coin operated means to control the movement of said bolt, and means to cause the packet resting upon said ejector plate to move longitudinally on said ejector plate, substantially as described.

3. The combination in a vending machine of a receptacle adapted to maintain a supply of packets in upright column, a division plate in said receptacle having a coin-slot therethrough, an ejector plate on said division plate, a pivot passing through said ejector plate adjacent to one end thereof, a tilting plate horizontally pivoted under said division plate, a lock-bolt secured on said tilting plate and extending upwardly through coinciding holes in said division and ejector plates, coin engaging means secured on said tilting plate, and means to disengage a coin therefrom when said ejector plate is opened, substantially as set forth.

4. The combination in a vending machine, of a packet receptacle, a packet ejector, a tilting plate, a lock-bolt secured thereto and adapted to engage and lock said ejector, coin engaging means on said tilting plate whereby said plate may be tilted when a coin is inserted, and means secured on said ejector adapted to engage said coin engaging means to release a coin when the ejector is operated, substantially as set forth.

In testimony whereof I affix my signature in presence of two witnesses.

CYRUS P. GIFFORD.
